UNITED STATES PATENT OFFICE

2,081,683

ELASTIC ATTACHING DEVICE

Abraham Solosko, Chicago, Ill.

Application July 7, 1936, Serial No. 89,297

5 Claims. (Cl. 132—58)

This invention relates to attaching devices, particularly attaching devices to be employed in connection with elastic filaments for use as hat elastics.

5 My invention has for its object the provision of a fastening tip which is applied to one or both ends of an elastic filament or strand and which includes provision for perforating a fabric material, to pass the strand through the fabric, 10 after which it may resist withdrawal through the perforated fabric, to anchor the end of the filament in position in relation to the fabric.

My invention is directed particularly to an attaching device associated with elastic bands, filaments or strands, employed to hold hats on the heads of the wearers, by the elastic tension inherent in the elastic strand, filament or band, avoiding the necessity for sewing such elements to the hat or similar article of apparel.

20 Where I have employed, in connection with elastic filaments, strands or bands, attaching tips which include a thin sheet metal tip formed into a perforating portion, a strand engaging portion and a guiding portion, in which the perforating 25 portion and the strand engaging portion are respectively of conical and cylindrical contour, with the free end of the strand or filament enclosed within the conical and cylindrical portion, in accordance with an attaching device described in 30 the patent to Schwartzman, No. 1,867,330, July 12, 1932, I have found that such device, while suitable for attachment to an inelastic string, rope or thread, made of textile material, does not adequately anchor itself to the elastic filament, web or strand, particularly where the latter 35 comprises one or more filaments of rubber encased within an enveloping braid or winding of textile material. The attempt to apply requisite pressure on a tip of the character referred to in 40 the aforementioned Schwartzman patent to an elastic filament serves either to sever the elastic or, upon tensioning the filament against the tip, causes release of the anchored end.

Accordingly, it is an object of my invention to 45 provide an anchoring tip for elastic filaments, webs, strands or ropes, particularly those which are employed as hat elastics, in which the attachment of the tip to the filament is peculiarly adapted for attachment to the elastic body 50 constituting the filament, especially where the elastic means constitute a core of one or more filaments of rubber.

It is further contemplated by my invention to 55 provide an attachment or anchoring device for elastic strands, filaments, ropes or bands, which avoids undue pressure of the attaching device to the filament or strand, which may otherwise sever the same or which so engages the elastic member 60 that the attenuation incident to the use of the

elastic will not release the elastic from the attaching or anchoring tip.

To attain these objects and such further objects as may appear herein or be hereinafter pointed out, I make reference to the accompanying drawing, forming a part hereof, in which—

Figure 1 is a perspective view showing my device in use as a hat elastic;

Figure 2 is a perspective view of my anchoring tip before attachment;

Figure 3 is a section taken on the line 3—3 of Figure 2;

Figure 4 is an enlarged longitudinal section of my device, with the elastic filament in position;

Figure 5 is a perspective view of my hat elastic and anchoring tips in position;

Figure 6 is a sectional view of my device in anchoring position on the fabric with which it is to be used;

Figure 7 is a plan view showing the blank from 20 which my attaching tip is made.

Making reference to the drawing, it is contemplated in the preferred form of my invention, to provide a hat elastic 10, having its free ends provided with anchoring tips 11 and 12.

25 For this purpose, where the elastic strand comprises a core of rubber and an encasing decorative fabric, either of braid or thread winding, I have found that completely encasing the free end of such material in a cylindrical or tubular tip, with firm connection between the attaching or anchoring tip and the strand, is inadequate as under tension the elastic strand attenuates and becomes free from the attaching or anchoring tip and such portions thereof which are employed to envelope the free end of this strand.

Accordingly, in accordance with my preferred form of the invention, I provide an elastic attaching or anchoring tip which avoids the problems incident to an anchoring tip of the character hereinabove referred to and described in the Schwartzman patent when some of the features thereof are employed in connection with an elastic strand, web or rope.

40 My attaching device or anchoring tip is preferably formed from thin sheet metal or similar deformable sheeting and comprises a body portion 13, stamped from a blank to include a perforating tip 14, extending into the filament attaching portion 15, of greater width, and terminating into a filament guiding portion 16.

45 It is preferred initially to subject the blank shown in Figure 7 to a shaping operation, providing a generally U-shaped channel, thus forming the attaching or anchoring tip with spaced branches 17 and 18, and a generally semi-cylindrical section 19. The stamping and/or shaping operation may be simultaneously accompanied by an operation which indents the base 20 of the channel with an inwardly directed lug 21.

With the tip thus provided, attachment of the tip to the elastic strand may now be accomplished and this may preferably be done by positioning the tip 13 into one member of a pair of dies, with the elastic strand positioned between the extended branches 17 and 18. There is then applied the deforming pressure which deforms the branches 17 and 18 into the strand enveloping position, preferably overlapping the same, as 10 more clearly shown in Figures 4 and 5.

It will be observed that the operation just described deforms the branches 17 and 18 so as to constrict the elastic at the portion 22 and leave unconstricted portions 23 and 24, to either side 15 of the indentation 21.

Thus, the strand in connection with the enveloping branches of the anchoring tip or attaching device, is constricted in part, leaving other portions of the strand unconstricted or in 20 a distended relation by reason of the fact that the branches 17 and 18 are so formed as not completely to envelope the strand, as will be clear from observing the relationship of the branches 17 and 18 in connection with the end 23 of the 25 filament 10.

Thus it will be observed that one of the primary features of my invention resides in the provision of an attaching or anchoring tip in which the elastic attaching sections include means for 30 constricting the elastic body and provides means for expanding or leaving the elastic in the distended condition within the structure comprising the attaching branches, inwardly from the end of the strand. Thus, tension upon the elastic strand in relation to the anchoring or attaching tip, tending to attenuate the elastic filament, 35 will leave a portion of the filament free from the attenuating action, thereby to prevent disengagement of the elastic filament or strand from the 40 anchoring or attaching tip.

While I have shown the preferred form of my invention, with filament enveloping sections 17 and 18 in overlapping position, in part, it will be understood that this is merely for exemplifying 45 one form of my invention which serves to provide filament attaching branches serving as filament constricting means and means to permit a distension of the elastic filament in relation to the attaching branches. However, the broader 50 phases of my invention contemplate the combination with an elastic filament, cord or web having an attaching or anchoring tip which includes attaching branches constricting the elastic filament, while providing means within the 55 body of the attaching tip between the end of the filament and the point of attachment, permitting extension of the elastic filament or leaving the elastic filament at such portions in an unconstricted condition, to leave this distended or unconstricted portion substantially free from the attenuating force, tending to release the anchoring or attaching tip from the elastic filament, strand, cord or web.

Therefore, though I have exemplified my invention in its preferred form, broader phases of my invention are set forth in the appended claims.

I claim:

1. A hat elastic or the like comprising, in combination, an elastic filament having affixed thereto an anchoring tip or attaching member comprising deformable sheet metal, including a perforating point and guiding portions at oppo-

site ends, with intermediate elastic attaching branches including portions constricting the elastic lying between the perforating point and the attaching branches and leaving portions of the elastic within the body of the tip unconstricted. 5

2. A hat elastic or the like comprising, in combination, a strand or filament having a rubber core, a free end thereof having affixed thereto an anchoring tip or attaching member comprising deformable sheeting material including a perforating point and a strand or filament guiding portion oppositely disposed thereto and intermediate branches substantially encasing said strand or filament and constricting the same in 15 part, with a free end of the strand adjacent the perforating point and leaving the end portions of said strand intermediate the perforating tip and branches unconstricted. 10

3. An attaching device comprising, in combination, a strand or filament of elastic material having its free ends provided with anchoring or attaching tips comprising deformable sheeting including a perforating point and a strand or filament guiding portion oppositely disposed in 20 relation to an intermediate body portion, said intermediate body portion comprising strand or filament engaging branches substantially encasing said strand or filament adjacent an end of the strand or filament, an indentation cooperating 25 with said branches and constricting said strand or filament, other portions of said tip between the piercing point and indentation being formed to leave said strand or filament between said branches and the strand or filament 30 end unconstricted. 35

4. An attaching device of the character described comprising, in combination, a strand or filament having an elastic rubber core having a free end provided with an anchoring or attaching 40 tip formed of deformable sheet metal including a perforating point and a substantially semi-cylindrically formed portion oppositely disposed in relation to an intermediate section having filament or strand engaging branches substantially 45 encasing said strand or filament and constricting the same inwardly from an end of the elastic strand or filament, with other portions of said branches providing means for permitting said filament or strand to expand or remain unconstricted between said branches and the end of the filament, said means for permitting the filament or strand to expand lying at a point between the constricting portions of said branches and the perforating point. 50 55

5. An attaching device of the character described comprising, in combination, a strand or filament of elastic material including a distensible rubber core having a free end provided with an anchoring or attaching tip comprising 60 deformable sheet metal including a generally triangularly formed perforating point and strand or filament engaging branches substantially encasing said strand or filament and constricting the same, portions of said branches of lesser 65 dimensions, leaving the strand or filament free to expand or remain unconstricted between portions of said branches and the strand filament end, said expanded portion of the filament being located at a point between the portions of the branches constricting the strand or filament and the perforating point of the tip. 70
